UNITED STATES PATENT OFFICE.

JAMES WEATHERS, OF INDIANAPOLIS, INDIANA.

SASH-BALANCE.

SPECIFICATION forming part of Letters Patent No. 334,628, dated January 19, 1886.

Application filed October 29, 1885. Serial No. 181,313. (No model.)

To all whom it may concern:

Be it known that I, JAMES WEATHERS, a citizen of the United States, residing at Indianapolis, in the county of Marion and State 5 of Indiana, have invented certain new and useful Improvements in Windows, of which the following is a specification, reference being had therein to the accompanying drawings.

My invention relates to improvements in 10 windows or vertically-moving doors and shutters, and is designed to produce a device whereby the sashes (in windows) will move automatically to what is commonly termed an "open position," they being normally retained 15 in a closed position.

Being aware of the disadvantages attending 20 the use of unguided springs that act to move the sash by their contractile force, I design to obviate the same by this invention, 25 which consists in utilizing the expansive force of a coil spring guided by rods in the casing in a manner hereinafter set forth.

I accomplish two objects not attained by 30 the devices referred to. First, by utilizing the expansive force of the spring the stretching and consequent weakening of the same is obviated, and, second, by using guiding rods, around which the spring is coiled, the sashes are guided and the said spring prevented from 35 crimping when contracted.

In the drawings, Figure 1 represents a front view of a window with parts broken away and sectioned; Fig. 2, a cross-section of one 35 side of the casing and sashes, and Fig. 3 a detail of a bearing plate located on the edge of the sash.

In the said drawings the upper and lower sashes are lettered A and B, respectively, and each has on each side a longitudinal 40 groove, C. Resting centrally in the spaces between the guide-strips D are rods E, secured in the top and bottom of frame and surrounded by the spiral springs F. On top the sashes, at each side, are firmly secured the 45 slotted plates G, the said slots being coincident with the ends of the grooves C, and of sufficient size to admit the passage of the rods E, but not of the springs F. Each sash is provided with a hook or catch, H, which engages with a stop on the casing or frame. The 50 springs F are of sufficient length and strength

to sustain the sash at the top of the casing. The upper sash, A, is normally retained in the said position, and when lowered is held by the catch H thereon, on releasing which 5 the springs immediately raise the said sash to its proper or elevated position. In the lower sash, B, the springs are normally compressed, and the catch holds the said sash in place. When released, the sash will automatically 6 rise. The plates G serve to strengthen the sash, to keep it running smoothly on the rods, and to form a bearing for the springs.

I wish to be distinctly understood as not broadly claiming springs which act by contraction in connection with window-sashes to 6 operate the same.

I am also aware that it is not new to bore 7 holes in the edges of the sash and insert springs in said recesses for the purpose of facilitating the operation of the sash.

It will be seen from the foregoing that the essential feature of this invention consists in providing the sash with longitudinal grooves for the reception of rigidly-secured rods, and 7 coiled springs surrounding said rod and acting by their extensible force.

This invention, as before stated, is equally applicable to doors, shutters, or the like when they are made to slide and are not hinged. 8

I claim—

1. Combined with a sash longitudinally grooved on each side, fixed rods extending the length of the frame and resting in said grooves, and springs surrounding said rods 8 and acting on said sash by their extensible force, substantially as specified.

2. Combined with a sash longitudinally grooved on the edges, fixed rods extending the length of the window-frame and resting in said grooves, springs surrounding said rods and normally contained within said grooves, and slotted plates on the sash coincident with said grooves and forming bearings for said springs, substantially as specified. 9

In testimony whereof I affix my signature in presence of two witnesses.

JAMES WEATHERS.

Witnesses:

JAMES YOUNG,
JESSE O. MATHENY.
